GRATE FOR GAS-RANGES.

1,168,852.

Specification of Letters Patent. Patented Jan. 18, 1916.

Application filed July 20, 1915. Serial No. 40,816.

To all whom it may concern:

Be it known that I, ROBERT B. CAVERLY, a citizen of the United States, residing at Philadelphia, in the county of Philadelphia and State of Pennsylvania, have invented 5 certain new and useful Improvements in Grates for Gas-Ranges, of which the following is a specification.

My invention relates to top grates for gas 10 ranges, and particularly to a top grate having a baffle plate adapted to extend downwardly inside the opening in the top frame of the gas range or stove, the grate resting on its outer edge portion on the top frame 15 adjacent to this opening. By means of the baffles referred to, the edges of the opening in the top frame are protected from the heat rising from the burners, the heat thereby being concentrated at the burner openings of 20 the grate with a resultant cooling of the top frame of the range. By this means, the economy of the operation of the range is materially increased, while at the same time the top frame of the range or stove is prevented 25 from becoming excessively hot, because of which fact I am enabled to provide the top frame with a flat enamel finish, which would be ruined if the top frame were permitted to become as hot as it would if my improvements 30 were not used. I preferably use the baffle plates referred to in connection with a pressed metal top grate which consists of a pressed metal structure formed of a single sheet with downturned flanges around the 35 outside edges, one or more openings, preferably star-shaped, and a plurality of stiffening flanges or corrugations which extend across the surface of the grate. These corrugations are so placed upon the plate as to 40 give stiffness to the structure, so that the same will not warp under severe heat tests, as well as securing other advantages. The grate rests upon its downturned edge flanges upon the surface of the top frame, the area 45 of contact between the grate and the top frame being small. The baffles referred to preferably comprise angular strips secured to the under side of the grate having flanges extending downwardly, as stated, adjacent 50 to but out of contact with the inner edges of the top frame. Preferably, a pair of grates are used together, mounted over the opening in the top frame with their inner edges abutting, each grate having baffle plates 55 secured adjacent to the three outside edges

thereof so that the baffle extends entirely around the pair of grates.

In order that a clearer understanding of my invention may be had, attention is hereby directed to the accompanying drawings 60 forming part of this specification and illustrating certain embodiments of my invention.

In the drawings, Figure 1 represents a plan view of a pair of grates mounted together, Fig. 2 is a vertical section taken on line 2—2 of Fig. 1, showing also the adjacent portions of the top frame of the range upon which the grate is mounted, Fig. 3 is a vertical section on line 3—3 of Fig. 1, and Fig. 4 is a partial bottom plan view of one 70 end of one of the grates.

Referring to the drawings, the grates 1 and 1' are each formed, as stated, of a single sheet of pressed metal, the edges of each 75 plate being flanged downwardly all the way around. The flanges at the outer sides and ends of each grate 2, 3 and 2', 3', respectively, may be made of the same height, while the flanges at the abutting inner edges 80 4 and 4' may be made of greater depth. Each grate is provided with a plurality of openings, such as the star point openings 5, 5', and the simmer openings 6, 6', the metal of the grate being flanged downwardly 85 around the lower edges of each opening, the metal of each grate also being pressed into a plurality of stiffening corrugations, such as is shown at 7, 7'.

The top frame of the stove may suitably 90 comprise a horizontal surface 8, as shown in Fig. 2, having an offset portion 9 on which the grates are adapted to rest, and a vertical flange 10 extending downward around the inside. This construction of top frame is, 95 of course, not essential for my invention, the top frame with which I prefer to use my grate being, however, preferably a pressed metal structure of the character referred to.

The grates are mounted in position with 100 their edge flanges 2, 3, 2', 3' resting on the offset portion 9 of the top frame. The baffles comprise strips 11, 12, 11', 12' secured to the under sides of the grates adjacent the ends and the outer side edges respectively. The 105 horizontal flanges of these baffle plates are secured by any suitable manner, such as welding, to the under sides of the grates adjacent to the edge flanges thereof, and have downwardly extending flanges 13, 13' 110

at their inner edges. These flanges 13, 13' extend downwardly inside the inner flanges 10 of the top frame, but out of contact therewith. The height of the edge flanges 2, 2', 5 3, 3' of the grates is greater than the thickness of metal comprising the horizontal portions of baffles 11, 12, 11', 12', so that the grates have contact with the top frame only along the edges of their contacting flanges 10 2, 3, 2' and 3', whereby the area of contacting surface through which heat may pass by conduction is reduced to a minimum.

Because of the provision of the baffles, as 15 described, the inner edges of the top frame are protected from heating, the heat from the burners underneath the grates being concentrated at the openings in the grates. Because of this the top frame of the range is maintained at a much lower temperature 20 than is usual in gas ranges, and the concentration of heat at the burner openings is such as to result in most economical operation. The baffle plates are preferably applied in the manner shown in Fig. 4, in which the 25 strips 11, 12 are shown as spot welded at 11^a, 12^a to the under side of the grate with their downturned flanges 13, 13' abutting at the corners.

Having described my invention, what I 30 claim as new therein and desire to secure by Letters Patent is:

1. The combination with a top frame of a range adapted to be given a flat enamel finish and having an opening therethrough, of a 35 grate mounted across the opening, comprising a single sheet of pressed metal having openings therethrough, downturned edge flanges resting on said top frame adjacent the opening therein to form the support for the grate, and having baffle plates secured to its under surface, said baffle plates having 40

vertical flanges extending downwardly within the top frame opening and parallel to and adjacent to edges thereof, but spaced from said edges and from said downturned edge 45 flanges, substantially as set forth.

2. The combination with a top frame of a range having an opening therethrough, of a pair of grates mounted across the opening side by side with abutting inner edges, said 50 grates having openings therethrough, downturned outside edge flanges resting on said top frame to form the supports for the grates and having baffle plates extending downwardly from their under surfaces parallel to but spaced from the edge flanges on the three outer sides of each, to form a complete baffle around the two grates, said baffle plates extending into the top frame opening 55 adjacent to but spaced from the edges thereof, substantially as set forth.

3. A top grate for gas ranges formed of a sheet of metal having openings therethrough and pressed to shape with its edges turned down to form supports for the grate, adapted to rest on a top frame of a range 60 adjacent to the opening therein, and flanged baffle plates secured to the under side of the grate parallel to three edges thereof, said baffle plates having downwardly extending 65 flanges joining at the corners, spaced sufficiently from the downturned edges to permit the same to extend into the opening in the top frame adjacent to the corresponding edges thereof, substantially as set forth.

This specification signed and witnessed 70 this 16th day of July, 1915.

ROBERT B. CAVERLY.
